CLAIM

An ornamental design for a claw keychain, as shown and described.

DESCRIPTION

FIG. 1 is a front perspective view of a claw keychain; FIG. 2 is a front elevational view of the keychain of FIG. 1; FIG. 3 is a rear elevational view of the keychain of FIG. 1; FIG. 4 is a right-side elevational view of the keychain of FIG. 1; FIG. 5 is a left-side elevational view of the keychain of FIG. 1; FIG. 6 is a top view of the keychain of FIG. 1; and, FIG. 7 is a bottom view of the keychain of FIG. 1. The broken lines are included for the purpose of illustrating portions of the claw keychain that form no part of the claimed design.
